UNITED STATES PATENT OFFICE.

CHARLES FRANCIS HUNTOON, OF CHICAGO, ILLINOIS, ASSIGNOR TO THE CHICAGO RAILWAY EQUIPMENT COMPANY, OF SAME PLACE.

SIDE BEARING FOR RAILWAY-CARS.

SPECIFICATION forming part of Letters Patent No. 606,345, dated June 28, 1898.

Application filed December 30, 1897. Serial No. 664,689. (No model.)

To all whom it may concern:

Be it known that I, CHARLES FRANCIS HUNTOON, a citizen of the United States, residing at Chicago, in the county of Cook, State of Illinois, have invented certain new and useful Improvements in Side Bearings for Railway-Cars; and I hereby declare the following to be a full, clear, and exact description of the same, reference being had to the accompanying drawings, in which—

Figure 1 is a side elevation of antifriction-roller side bearing embodying my invention in its simplest and preferred form. Fig. 2 is a bottom plan view of the side bearing shown in Fig. 1. Fig. 3 is a transverse vertical central section of the frame or carriage of the side bearing, the roller being shown in elevation. Fig. 4 is a side elevation of a similar side bearing, showing a plurality of rollers; and Fig. 5 is a bottom plan view of the multiple-roller side bearing illustrated in Fig. 4.

Like symbols refer to like parts wherever they occur.

My invention relates to that class of devices commonly termed "side bearings for railway-cars," having for their object to reduce the friction between the truck and body-bolster in curving, and my present invention has been more especially designed for attachment to the body-bolster.

Heretofore in this class of devices the journals of the rollers or the rollers themselves, as usually constructed, have traveled in a common track, going and coming in the same plane, and therefore liable to become nudged or jammed at the end of their travel in either direction, and so remain for a time at least, which subjected them to a sliding movement, which ultimately flattened the rollers and destroyed their usefulness as antifriction-bearings. To overcome this defect, side bearings have heretofore been devised and applied wherein when the load was lifted from the bearing the rollers would be automatically returned to the center (self-centering) by means of a spring or some equivalent resilient medium.

The object of the present invention is to simplify this latter class of what may be termed "self-centering side bearings," and this I accomplish by combining with an anti-

friction-roller a suspension-frame having an upper or horizontal track and a lower centrally-inclined track, whereby when the roller is freed from the load it will free itself from contact with the upper or horizontal track and gravitate toward the center, traversing the lower or inclined track with a rolling motion, so that the roller shall always present a new face to its tracks, and such a construction embodies the main feature of my invention.

In carrying out my invention I prefer to provide each roller with independent trunnion-slots having a plain upper edge or bearing, upon which the trunnions travel away from the center when carrying the load, and an arc-shaped lower edge, on which the trunnions travel by gravity back to the center of the bearing when relieved of the load, and such a construction embodies a secondary feature of my invention.

There are other minor features of invention, all as will hereinafter more fully appear.

I will now proceed to describe my invention more fully, so that others skilled in the art to which it appertains may apply the same.

In the drawings, 1 indicates a suitable carriage or frame in which are journaled the rollers constituting the antifriction-bearings. The frame or carriage 1 is intended to be secured to or suspended from the body-bolster of a railway-car in the usual manner, and for that purpose is provided with the perforated lugs 2 or equivalent means, and the sides 1^a 1^b of the frame, in which the roller-trunnions are journaled, are preferably arranged as concentric arcs, each having a journal-slot 3, the upper edge 3^a of which is a plain surface or track on which the journal travels away from the center when carrying the load, while its lower edge 3^b is an arc whose lowest point is at the center, said curved edge constituting a track over which the roller-journal travels toward the center by gravity as soon as the load is lifted from the rollers. Owing to the suspension of the devices from the body-bolster the roller will, when freed from the load, drop down or free itself from the upper track, so that its return movement is not hampered or otherwise affected by contact with the upper track.

4 indicates the antifriction-roller, having

trunnions 4^a, which enter and travel in the journal-slots 3. In order that the roller 4 shall travel in a true arc described from the center of the truck, the face and trunnions of roller 4 are tapered on lines which would, if extended, converge on the center lines of the car-bolster.

The frame 1, with its sides 1^a 1^b, having slots 3, may be formed in any suitable manner, but is preferably a malleable casting having one detachable section or bar 5 to permit of the introduction of the roller 4.

The side bearing, being constructed as hereinbefore set forth, will operate as follows:

15 The roller, while leaving the center and carrying the load, will travel on the upper straight edge 3^a of the slot until it reaches the limit of its travel, and when the load is removed it will drop down or free itself from the upper track and travel back to the center on the curved lower edge 3^b of the slot, continuously rotating in the same direction, so that a fresh bearing or contact surface of the roller with the track is constantly presented, and there can be no 25 sliding or flattening of the roller.

The construction shown in Figs. 4 and 5 of the drawings is but a duplication of that shown in Figs. 1 to 3 and heretofore described, and so requires no further description.

30 Having thus described my invention, what I claim, and desire to secure by Letters Patent, is—

1. In a side bearing for railway-cars, the combination with an antifriction-roller, of a 35 suspension frame or carriage having an upper

horizontal track and a lower centrally-inclined track; substantially as and for the purposes specified.

2. In a side bearing for railway-cars, the combination with a suitable frame provided with journal-slots having a plain upper edge and an arc-shaped lower edge, of an antifriction-roller having trunnions journaled in said slots, substantially as and for the purposes specified. 45

3. In a side bearing for railway-cars, the combination with a suspension frame or carriage having arc-shaped concentric sides, each side having a journal-slot constituting a horizontal upper and a centrally-inclined lower track, of an antifriction-roller having trunnions the face and trunnions of said roller tapering on lines converging to the center of the car-bolster; substantially as and for the purposes specified. 50

4. In a side bearing for railway-cars, the combination with an antifriction-roller provided with trunnions, of a suspension frame or carriage having slots for the reception of the trunnions of the roller, and provided with a detachable section or bar constituting the bottom of one of said trunnion-slots; substantially as and for the purposes specified. 55

In testimony whereof I affix my signature, in presence of two witnesses, this 28th day of December, 1897.

CHARLES FRANCIS HUNTOON.
